UNITED STATES PATENT OFFICE.

JOSEPH A. POIRIER, OF WOONSOCKET, RHODE ISLAND.

CARRIAGE FOR LAYING CLOTH.

Application filed July 21, 1922. Serial No. 576,623.

To all whom it may concern:

Be it known that I, JOSEPH A. POIRIER, a citizen of the United States, residing at Woonsocket, in the county of Providence and State of Rhode Island, have invented a new and useful Carriage for Laying Cloth, of which the following is a specification.

This invention relates to certain improved devices by which the operation of laying out cloth for the cutting trade may be made less laborious and by which the time required for laying the cloth may be greatly reduced. It is customary to lay out the cloth on a long table, repeatedly adding layers or strips of cloth until the desired number of layers is accumulated. These tables may be from 50 to 100 feet in length and the number of layers of cloth required is often very large. It has been the common custom for a workman or boy to take the ends of one or two pieces of cloth and walk the length of the table, drawing the cloth with him and depositing it on the strips previously laid. He then returns to the starting point, cuts the ends of the cloth, and proceeds to repeat the operation. This method of laying cloth is slow and laborious and requires the workman to walk many miles in laying out a lot of cloth.

It is the object of my present invention to provide mechanism associated with the cutting table, by which the operator may be easily transported from one end to the other of the table and by which he may be as quickly returned to the starting position.

A further object is to provide special forms of controlling devices by which the operator may cause the mechanism to move at will in either direction and by which he may stop the machine at a definite point at each end of the path of travel thereof.

My invention further relates to arrangements and combinations of parts which will be hereinafter described and more particularly pointed out in the appended claims.

A preferred form of my invention is shown in the drawings in which—

Fig. 1 is a front elevation of a cutting table having my improved mechanism associated therewith;

Fig. 2 is a plan view of the travelling carriage;

Fig. 3 is a sectional elevation, taken along the line 3—3 in Fig. 2;

Fig. 4 is a detail front view, looking in the direction of the arrow 4 in Fig. 2;

Fig. 5 is a side elevation partly in section, looking in the direction of the arrow 5 in Fig. 4;

Fig. 6 is a vertical sectional view, taken along the line 6—6 in Fig. 2; and

Fig. 7 is a sectional plan view of certain parts, taken substantially along the line 7—7 in Fig. 6.

Referring to the drawings, I have shown a cutting table 10 having legs or supports 11 and having a pair of guide rolls or bars 12 and 13 mounted at one end of the table. The cloth is commonly furnished in folded bundles or packages, two of which may be placed in separate compartments in a box or casing 14 at one end of the table. The ends of the cloth are drawn from the box 14 over the elevated guides 12 and 13 and are carried to the opposite end of the table where they may be retained by placing a weight 15 thereon. The cloth is then cut adjacent the guides 12 and 13 and the ends are again carried to the opposite end of the table.

The parts thus far described are of the usual form and in themselves constitute no part of my present invention which relates to the provision of a travelling carriage so associated with the table that the operator may be conveniently transported back and forth alongside the table. For this purpose, I have provided a carriage comprising a platform 16 mounted on wheels 17 which are adapted to travel along tracks or guideways 18 adjacent the side of the table and substantially parallel thereto.

A motor 20 is mounted on the platform 16 and is connected by a belt 21 to a pulley 22 rotatable on a stud or shaft 23 (Fig. 5) fixed in a post or standard 24 secured to the platform 16. A drum 25 (Fig. 2) is secured to the pulley 22 and rotates therewith.

A wire or cable 26 extends parallel with the tracks 18 and is preferably supported upon the legs 11 of the table. This cable 26 makes one or more turns around the drum 25 to which it may be guided by a pair of grooved rolls 27. As the cable 26 is fixed in longitudinal position, it will be apparent that rotation of the drum 25 will result in movement of the carriage along its guideways toward one end or the other of the table.

Electric current for the motor 20 may be delivered to the carriage in any con-

venient way and I have shown herein a three wire cable 30 formed in a succession of loops attached to rings 31 slideable on a plurality of guide wires 32 supported above the table 10. This permits the carriage to travel back and forth without entangling itself in the loose cable and also avoids the necessity for a trolley or other movable contact device.

10 The connections from the cable 30 to the motor are preferably formed through forward and reverse switches, each comprising a pair of fixed contact plates 33 or 34 and a pair of yielding or movable contact plates 35 or 36. These different contact plates are secured to the under side of the platform 16 and are normally in the spaced or open relation shown in Fig. 6.

A fibre plate 37 rests upon the movable 20 contact plates 35 and is provided with a plunger 38 extending above the platform 16. A similar fibre plate 39 rests on the contacts 36 and is provided with a plunger 40.

25 When the plunger 38 is depressed, the circuit is closed through the plates 33 and 35 to start the motor and move the carriage in one direction. The plungers 38 and 40 project upward through the platform 16 in convenient position for operation by the foot of an operator mounted upon a seat 44 above the platform 16.

It is essential that only one of the plungers 38 and 40 shall be depressed at a given 35 time and accordingly I have provided a safety device which prevents simultaneous operation of both plungers. This safety device comprises a lever 41 pivoted at 42 to a bracket 43 secured to the under side of the 40 platform 16. The ends of the lever 41 project beneath the fibre plates 37 and 39 and are engaged by the plates or by some part fixed thereto whenever either plunger is depressed. With this construction, the depression of one plunger necessarily requires that the other plunger remain in its normal or raised position. It is therefore impossible to close both the forward and reverse circuits at the same time.

50 It is desirable that the carriage be stopped at a definite position at each end of its path of travel and for this purpose I provide a lug or projection 45 (Figs. 4 and 5) on one side of the pulley 22. I also provide a lever 55 46 pivoted at 47 to the support 24 and having side arms 48 extending on each side of the support 24. A spring 49 normally holds the lever 46 in the position shown in Fig. 5.

The lower end of the lever 47 is engaged 60 by a foot lever 50, depression of which throws the arms 48 into the path of the projection 45 on the pulley 22. The pulley will thus be stopped in a definite position when the projection 45 thus engages one or the

other of the arms 48, depending upon the direction of travel of the carriage.

With the use of the mechanism above described, the operator is able to move rapidly from one end to the other of the table, carrying the layers of cloth with him in one direction and returning quickly to the starting point. It should be noted that the contacts are all normally open and that the carriage will move only so long as one or the other of the plungers 38 or 40 is depressed. The operator is thus required to hold his foot on one or the other plunger in order to move the carriage and he naturally uses the same foot to operate the foot lever 50 which advances the stop. This arrangement gives reasonable insurance that the current shall be cut off from the motor before the stop is advanced to operative position. By the use of this improved mechanism, the cloth can be laid out at greatly increased speed and the laborious features of the operation are entirely avoided.

Having thus described my invention and the advantages thereof, I do not wish to be limited to the details herein disclosed otherwise than as set forth in the claims, but what I claim is:—

1. A device for laying cloth comprising a cloth table, a wheeled carriage, guide-ways therefor adjacent said table, a motor on said carriage effective to propel said carriage along said guide-ways, and foot operated controlling devices for said motor, said devices comprising forward and reverse switches, means to close each switch and means to prevent simultaneous closing of both switches.

2. A device for laying cloth comprising a table, a wheeled carriage, guide-ways therefor adjacent said table, a motor on said carriage effective to propel said carriage along said guide-ways, and controlling devices for said motor, said devices comprising forward and reverse switches, a plunger to close each switch and a lever pivoted adjacent said plungers and engaged thereby, said lever preventing simultaneous depression of both plungers.

3. A device for laying cloth comprising a table, a wheeled carriage, guide-ways therefor adjacent said table, a cable extending substantially parallel to said guide-ways and fixed relatively to said table and guide-ways, a motor on said carriage, connections from said motor to said cable, controlling switches for said motor normally held yieldingly in open position, foot-operated devices to close a selected switch, and foot-operated means to stop said carriage.

4. A device for laying cloth comprising a table, a wheeled carriage, guide-ways therefor adjacent said table, a cable extending substantially parallel to said guide-ways

and fixed relatively to said table and guide-ways, a motor on said carriage, connections from said motor to said cable, controlling switches for said motor normally held yieldingly in open position, foot-operated devices to close a selected switch, and foot-operated means to stop said carriage, said means comprising a projection rotating with said drum and a stop arm movable into the path of

10 said projection to stop rotation of said drum.

5. A device for laying cloth comprising a table, a wheeled carriage, guide-ways therefor adjacent said table, a cable extending substantially parallel to said guide-ways and 15 fixed relatively to said table and guide-ways, a motor on said carriage, connections from said motor to said cable and controlling devices for said motor including forward and reverse switches for said motor each com-

prising a pair of contacts, a plate of non- 20 conducting material engaging each pair of contacts, means to depress said plates to close said contacts, and a device preventing simultaneous depression of both plates.

6. A device for laying cloth comprising a 25 table, a wheeled carriage, guide-ways therefor adjacent said table, an electric motor to propel said carriage along said guide-ways in either direction, means to control and stop said carriage, an electric cable connected to 30 said motor and to a fixed outlet, a plurality of elevated guide wires disposed parallel to said table and guide-ways and a plurality of devices slidable on said wires and supporting said cable in a series of loops. 35

In testimony whereof I have hereunto affixed my signature.

JOSEPH A. POIRIER.
